UNITED STATES PATENT OFFICE.

HENRY BROOKER, OF GOODMANYES, ENGLAND.

COIN-FREED DELIVERY APPARATUS.

1,398,766.

Specification of Letters Patent.

Patented Nov. 29, 1921.

Application filed December 27, 1920. Serial No. 433,403.

To all whom it may concern:

Be it known that I, HENRY BROOKER, a subject of the King of Great Britain and Ireland, residing at Goodmayes, in the 5 county of Essex, England, whose post-office address is 43 Castleton road, Goodmayes, in the county of Essex, England, have invented certain new and useful Improvements in and Relating to Coin-Freed Delivery Apparatus, 10 (for which I filed an application for patent in Great Britain on January 28, 1919;) and I do hereby declare the following to be a full, clear, and exact description of the invention, 15 such as will enable others skilled in the art to which it appertains to make and use the same.

This invention relates principally to the type of coin-freed delivery apparatus in which mechanism is energized or wound up 20 and thus set in condition for the automatic delivery of an article, for instance a ticket, a box of matches, packet of sweets, or other article, by the insertion of a predetermined coin or coins, the coin or coins inserted also 25 effecting the release of the mechanism which then acts to deliver the article from the machine.

In a machine according to this invention 30 tickets or other articles to be delivered by the machine are arranged in a column or pile on the top of which column a weighted follower may be placed, the tickets or articles and follower being maintained and working in a suitable guide-way or frame.

The invention has for its object an improved delivery mechanism which, although 35 particularly designed for delivering rail-way and like tickets from machines in which a plurality of coins of the same or different values are or may be inserted to set the machine in condition for the delivery of the ticket, may be employed in other forms of coin-freed apparatus and is suitable for delivering other articles, and which is certain 40 and reliable in its action, is simple in construction, and relatively light in weight.

The invention further consists in the construction, combination and arrangement of parts as pointed out in the claims, or as 45 hereinafter described with reference to the accompanying drawings, in which,

Figure 1 is a side elevation of a delivery mechanism according to this invention adapted to deliver card-board or paste board 50 tickets such as those used on railways,

Fig. 2 is a plan of the delivery mechanism shown in Fig. 1, and

Figs. 3, 4 and 5 are respectively plan, side elevation and end elevation of a guideway for the moving frame or carriage of the delivery mechanism hereinafter described.

Like reference numbers indicate like parts in the several figures of the drawings.

Referring to the drawings, 1 indicates the front plate of the casing of the machine and 65 2 a cross plate providing support for certain parts of the mechanism. The plate 2 is not shown in Fig. 1. 3 is the bottom portion of a main lever or rocking bar pivoted at or toward its upper end on the plate 2 and is 70 adapted to be acted upon by the insertion of the required coin or coins and thereby moved to the right Figs. 1 and 2 into position to be released and effect delivery of a ticket as 75 hereinafter described. The coin operated mechanism may be the same as that described in the specification of my British Letters Patent No. 114,476 or in the specification of my British Letters Patent No. 141,135, or may be of any other 80 convenient construction. The tickets which for the sake of clearness are not shown in the drawings are supported in a pile or column by a bottom plate 4 secured to the front plate of the machine and provided 85 with a pair of slots or cut away portions 5, 5, and suitable upright members or guides are provided to keep the tickets properly in column,—as shown four angle pieces or uprights 6 secured together by front and back 90 plates or strips 7, 8 respectively and side plates or strips 9, 9, the latter being in turn secured to the front plate 1 of the machine. The pair of angle pieces or uprights 6 toward the rear of the machine have their rear 95 members cut away at their lower ends as indicated in dotted lines at 6^a Fig. 1, to permit withdrawal of the lowermost ticket of the pile or column, as will be hereinafter described. Pivotaly mounted on a pin 10 secured to the lower end of lever 3 is a U-shaped frame 11, the forward end of which is provided with a cross bar 12 the extreme 100 end portions of which rest on lower guide plates or members 13, 13 suitably secured in 105 a fixed position in the machine. As shown one of the guide members 13 is fixed to the front plate 1 and the other to the transverse plate 2. Each guide member 13 carries an upper guide member 14 formed by a portion 110

of spring metal of the desired shape, the member 14 being secured to member 13 by screws such as 15, and having its forward end 14^a bent downwardly in a gentle curve 5 so as to touch, or nearly touch, the guide surface of the member 13. The frame 11 is provided with front and rear ticket engaging projections or members 16, 17, the front members 16 being suitably mounted on a 10 cross bar 16^a whose downturned ends 16^b are mounted on and secured close to the ends of the cross-bar 12 so as not to turn or revolve in relation thereto, and the rear projections or members 17 being suitably secured in place 15 on and being carried by a pair of cross bars 18 of the frame 11 which pass through holes in tail portions 17^a. 18^a are ferrules or distance pieces on the cross bars 18.

A suitably fixed plate or guideway 19 is 20 provided and secured to the front plate 1 of the machine by means of a downwardly turned portion 19^a. The forward portion of the guide plate 19 is horizontal while the rear portion slopes upwardly. Suitable 25 slots 20, 20, and 21 are cut in the rear portion of the guide plate 19, the slots 20, 20 being to accommodate the upstanding projections or members 17 on the moving frame 11, and the slot 21 to accommodate an upward standing cam 22 also mounted on the cross bars 18 and thus carried by the moving frame 11, which is adapted in the operation of the machine to act on and raise a plate 23 pivotally mounted at 24 on the guide plate 30 19. This plate 23 is provided with a slot 35 extending from the pivotal edge approximately half-way toward its forward edge, the slot being in Fig. 2 coincident with the rear portion of the slot 21. 25 is a stop to 40 limit the upward movement of the plate 23. If desired a suitable spring may be provided tending to press the plate 23 downwardly.

The forward portion of the guide plate 45 19 is so arranged that its upper surface coincides or registers exactly with the lower surface of the ticket delivery slot 26 in the front plate 1 of the machine and said forward portion of the plate 19 has upturned 50 sides or edges which in turn have secured to them inwardly projecting portions 19^b between which and the plate 19 the ticket passes to the delivery slot 26. The rear or sloping portion of the plate 19 also has its 55 sides or edges upturned but these upturned portions are carried upwardly to form side guides or wings 19^c. It will be understood that the parts 19^b may if desired be formed integral with the plate 19. A suitable 60 weight or follower may, and preferably would, be provided on top of the pile or column of tickets.

The working of the mechanism illustrated is as follows:—

65 The insertion of the correct coin or coins

into the machine causes the lever 3 to move rearwardly,—i. e. to the right Figs. 1 and 2,—and thus also moves the frame 11 toward the rear of the machine. On the frame 11 commencing to move the ends of 70 the cross bar 12 engage and travel up the down-turned ends 14^a on to the top of the upper guide members 14, the forward end of the frame 11, and consequently the cross bars 12 and 16^a, being thus raised. The 75 projections 16 are thus raised and pass upwardly through the slots 5 into position to engage the forward edge of the bottom ticket of the pile or column of tickets resting on plate 4. The rearward movement 80 of the lever 3 and frame 11 may be one continuous movement or may be in steps or stages according to whether one or a plurality of coins are employed to "set" the machine and cause delivery of a ticket, but 85 the operation of the delivery mechanism is the same in either case. In the rearward movement of the frame 11 the ends of the cross-bar 12 travel along the top of the guide members 14 and the projections 16 draw the 90 bottom ticket rearwardly and under the pivotal plate 23. The cam 22 of course moves rearwardly with the frame 11 and by the time the ticket is clear of the plate 4 the cam 22 will have ceased to support the plate 95 23, having passed into the slot in the plate, and the plate will fall by its own weight (or it may be assisted by a spring) on to the ticket and press same on to the rearward or sloping portions of the guide way 19. In 100 the final portion of the rearward movement of the frame 11 the ends of the cross bar 12 pass off the rear ends of the upper guide members 14 and drop on to the lower guide members 13, which causes the projections 105 16 also to drop or move downwardly, so that in the return movement of the frame 11 the ends of the cross bar 12 travel along the lower guideway 13 lifting and moving past the down-turned ends 14^a of the upper 110 guide members 14 in the final portion of the forward movement. The return or forward movement of the lever 3 and frame 11 take place automatically, being moved by a returning spring connected to lever 3 or 115 other means,—when the coins fall or otherwise act on a trip or other release mechanism. In such return or forward movement of the frame 11 the ticket just withdrawn from the bottom of the pile or column 120 is moved forwardly by the projections 17 engaging its rearward edge and in its forward movement it abuts against the rearward edge of the ticket previously withdrawn (which is lying on the guide 19 below the pile or column of tickets) and ejects same through the ticket delivery slot 26, the ticket last withdrawn from the pile remaining in the machine. In the return or 125 forward movement of the frame 11 the cam 130

22 acts on the pivoted plate 23 and moves same upwardly so that it again takes the position shown in Fig. 1, the other parts of the delivery mechanism also returning to 5 the positions shown in Fig. 1.

It will be understood that when set for coin-free operation the frame 11 would be operated once by hand so that a ticket is set in position in the guideway 19 ready 10 to be ejected by the ticket withdrawn from the column or pile when the machine is first operated by the insertion of the coin or coins, and that thereafter a ticket will always be in the guideway ready for delivery.

If desired suitable anti-friction rollers or like devices may be provided for easing the movements of the frame 11. For instance anti-friction rollers might be provided on the ends of the cross-bar 12 to 20 prevent friction of said ends on the guides 13 and 14.

The mechanism above described and illustrated in the drawings, subject of course to the necessary modifications, as for instance in the size and shape of the guideway, is suitable for delivery of other articles than tickets, such for instance as packets of cigarettes, sweetmeats, matches, etc., and it 30 is to be understood that the invention is not limited to the delivery of tickets. The invention is also not limited to the details of construction shown in the drawings as these might be varied without departing 35 from the main features of the invention.

What I claim as my invention and desire to secure by Letters Patent is:—

1. In a delivery apparatus, a support for a pile of articles, a guideway for the articles 40 having a main portion arranged under the said support and having an extension which projects at the rear of the support, and a slidable delivery device provided with front and rear projections which operate alternately to slide the bottom article from under the pile and discharge it onto the said extension when moved rearwardly, and to slide the article off the extension onto the main portion of the guideway when moved 45 forwardly, whereby the article thus moved forwardly is enabled to push a similar article, previously moved forwardly, from the guideway.

2. In a delivery apparatus, a support for 55 a pile of articles, a guideway for the articles having a substantially horizontal main portion arranged under the said support and having an upwardly and rearwardly inclined extension arranged to the rear of the 60 support, and a slidable delivery device provided with front and rear projections which operate alternately to slide the bottom article from under the pile and discharge it onto the said extension when moved rearwardly, and to slide the article off the ex-

tension onto the main portion of the guideway when moved forwardly, whereby the article thus moved forwardly is enabled to push a similar article, previously moved forwardly, from the guideway.

3. In a delivery apparatus, a support for a pile of articles, a slotted guideway for the articles having a main portion arranged under the said support and having an extension which projects at the rear of the 70 support, and a slidable delivery device arranged below the said guideway and having front and rear projections which project upwardly through its slots and which operate alternately to slide the bottom article from under the pile and discharge it onto the said extension when moved rearwardly, and to slide the article off the extension onto the main portion of the guideway when moved forwardly.

4. In a delivery apparatus, a support for a pile of articles, a guideway for the articles having a main portion arranged under the said support and having an extension which projects at the rear of the support, a 80 slidable delivery member, a crossbar provided with front projections for engaging with the front edge of the bottom article of the pile, said crossbar being arranged above the said guideway and operatively connected 85 with the said delivery member, and rear projections on the said delivery member for engaging with the rear edge of an article discharged from the pile, said front projections operating to discharge the bottom article from the pile onto the said extension, and said rear projections operating to slide the article forwardly off the extension onto the main portion of the guideway under the crossbar.

5. The combination, with a delivery apparatus as set forth in claim 1, of means for pressing the article downwardly upon the said extension before the article is slid forwardly off it and onto the main portion of 110 the said guideway.

6. The combination, with a delivery apparatus as set forth in claim 1, of a plate pivoted to the rear end portion of the said extension and operating to press the article 115 downwardly upon it before the said article is slid forwardly onto the main portion of the said guideway.

7. The combination, with a delivery apparatus as set forth in claim 1, of a plate 120 pivotally supported by the said extension and operating to press the article downwardly upon it before the article is slid forwardly onto the main portion of the said guideway, and means carried by the said 125 slidable delivery device and operating to raise the said plate before the article is discharged onto the said extension.

8. The combination, with a delivery apparatus as set forth in claim 1, of guiding 130

devices for the said slidable delivery device which constrain it to slide in two superposed planes so that its projections do not engage with the bottom article of the pile during its forward movement.

9. The combination, with a delivery apparatus as set forth in claim 1, of lower guides which support the said slidable delivery device during its forward movement, and upper guides having inclined front end portions which operate to raise the said de-

livery device at the commencement of its rearward movement so that its front projections may engage with the bottom article of the pile.

In testimony whereof I have affixed my signature in presence of two witnesses.

HENRY BROOKER.
